AUTOMOBILE

Keamon Kurose, 7002 N. Mercer Way,
Mercer Island, Wash.

Filed Oct. 23, 1964, Ser. No. 32,299

Term of patent 14 years

(Cl. D14—3)

FIGURE 1 is a plan view of an automobile showing my new design with the top omitted for convenience of illustration.

FIG. 2 is a side elevation of the same, the side opposite being similar in appearance.

FIG. 3 is a front end view of the same.

FIG. 4 is a rear end view of the same.

The dominant features of my design reside in the solid line portions.

I claim:

The ornamental design for an automobile, substantially as shown and described.
